(57) **CLAIM**

The ornamental design for a cat lamp, as shown and described.

DESCRIPTION

FIG. 1 is a left, front and top side perspective view of a cat lamp showing my new design;

FIG. 2 is a front plan view thereof;

FIG. 3 is a rear plan view thereof;

FIG. 4 is a left plan view thereof;

FIG. 5 is a right plan view thereof;

FIG. 6 is a top plan view thereof; and,

FIG. 7 is a bottom plan view thereof.

The broken lines shown in the drawings illustrate portions of the article and form no part of the claimed design.
